Primary Examiner — Amy C Wierenga*Assistant Examiner* — Andrea Marie McKay(74) *Attorney, Agent, or Firm* — Birch, Stewart, Kolasch & Birch, LLP(57) **CLAIM**

We claim the ornamental design for a water heater, as shown and described.

DESCRIPTION

FIG. 1 is a front perspective view of a water heater showing the new design;

FIG. 2 is a rear perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines represent portions of the water heater that form no part of the claimed design.
